UNITED STATES PATENT OFFICE.

ELIZABETH HONGLER, OF PHILADELPHIA, PENNSYLVANIA.

SNAP-FASTENER.

1,282,084.

Specification of Letters Patent. Patented Oct. 22, 1918.

Application filed March 31, 1917, Serial No. 158,848. Renewed April 13, 1918. Serial No. 228,499.

To all whom it may concern:

Be it known that I, ELIZABETH HONGLER, a citizen of the United States, residing at Philadelphia, in the county of Philadelphia and State of Pennsylvania, have invented new and useful Improvements in Snap-Fasteners, of which the following is a specification.

The principal object of the present invention is to provide a snap fastener characterized by simplicity, efficiency, cheapness of manufacture and by the ease, accurateness and rapidity with which the same may be stitched to place and by the ease and rapidity with which the parts may be unclasped. A further object is to relieve strain upon the stitches by which the snap fastener is secured thereby reducing to a minimum the possibility of tearing during an unclasping period the fabric to which the snap fastener is attached. A further object of the present invention is to provide a snap fastener which requires less material in its manufacture than do standard forms of snap fasteners now upon the market, but which in assembled positions has substantially the same appearance as standard forms of snap fasteners. A further object of the present invention is to provide a snap fastener characterized by certain new and novel arrangements, connections and constructions of parts as will hereinafter more fully appear.

The invention consists of the improvements hereinafter described and finally claimed.

The nature, characteristic features and scope of the invention will be more fully understood from the following description taken in connection with the accompanying drawings forming part hereof and in which:

Figure 1 is a view in plan of the female member of the snap fastener;

Fig. 2 is a similar view of the male and female members in co-acting relation.

Fig. 3 is a view in section taken upon the line 3—3 of Fig. 2; and

Fig. 4 is a view in plan of a modified form of snap fastener.

For the purpose of illustrating my invention, I have shown in the accompanying drawings forms thereof which are at present

preferred by me, since the same have been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings and more particularly to Figs. 1 to 3 in which the preferred form of the invention is illustrated, the female member of the snap fastener is designated 1 and the male member 2. The recessed portion of the female member 1 is provided with a latch spring 3 for co-operatively engaging the head 4 of the male member 2 to retain the parts in co-acting relation. The thin, flat portions of the members 1 and 2 are each of elongated structure and longitudinally considered the edges thereof are inversely curved, that is, the width of said flat portions is reduced by cutting away the material thereof upon curved lines 5. Laterally considered, the edges of each of said flat portions of said members 1 and 2 are conversely curved. The members 1 and 2 are adapted when co-acting to have the longitudinal axes thereof disposed substantially at right angles to one another so that the conversely curved edges of one member projects beyond the inversely curved edges of the other member to provide a circular effect of disk-like contour, see Fig. 2. Thus assembled, the members 1 and 2 give the general effect of a standard form of snap fastener. Provided adjacent the conversely curved edges of the members 1 and 2 are stitch accommodating apertures. In practice slots 6 have been found to give best results although other forms of eyes may be employed. Such slots are provided with notched portions 7 for accommodating the threads of the stitching by which the members 1 and 2 are affixed to a fabric whereby the members 1 and 2 are more firmly held in place. Obviously, such notches may be omitted if desired. As the members 1 and 2 co-act with their longitudinal axes disposed substantially at right angles it will be observed that the slots 6 are so exposed that the members 1 and 2

may be readily sewn to place while in co-acting relation. Thus necessity for marking the desired position of the members 1 and 2 as required in standard snap fasteners 5 is eliminated. In order that the members 1 and 2 may be held against rotation with respect to one another, one member is provided with a projection 8 and the other member is provided with apertured portions 9 10 so that when the members 1 and 2 are in co-acting relation the projections are accommodated by said apertured portions to interlock said members.

In the modified form shown in Fig. 4, the 15 longitudinal edges of the members 1 and 2 are formed upon straight lines instead of curved lines as in the foregoing figures. Stops 10 are provided on one member adapted to engage with the edges of the other 20 member to prevent rotation of said members with respect to one another.

In the use of the above described snap fastener, the parts may be readily unclasped by employing the fingers of one hand to lift 25 the extended ends of one member while the fingers of the other hand are employed to hold the extended ends of the other member. It will be apparent that because the elongated members 1 and 2 are disposed at substantially right angles to one another, these 30 extended ends are quite prominent and may be readily grasped by the fingers in order to press the members apart. In the standard or circular form of snap fastener it is necessary to use the finger nails in pressing the 35 members apart.

It will now be apparent that I have devised a novel and useful construction which embodies the features of advantage enumerated as desirable in the statement of the invention and the above description and while I have in the present instance shown and described the preferred embodiments thereof, which have been found in practice to 45 give satisfactory and reliable results, it is to be understood that the same are susceptible of modification in various particulars without departing from the spirit or scope of the invention or sacrificing any of its advantages.

Having thus fully described my invention, what I claim as new and useful, is:

1. A snap fastener comprising two complementary members each having an oblong 55 body adapted to coact, with their longitudinal centers at right angles to each other so that the ends of each project beyond the side edges of the other, the body of each member having sewing slots therein, said 60 slots being located adjacent the ends, said slots having notches formed in their outer edges and lugs or projections formed with the body of one member and adapted to engage the body of the other member to prevent 65 the rotation of the members relative

to one another after they have been fastened together.

2. A device of the character stated comprising male and female, elongated members adapted when co-acting to have the longitudinal axes thereof disposed substantially at right angles to one another, the respective members being conversely curved laterally considered, so that the combined conversely curved parts form a circular effect in the said co-acting relation of members and means for interlocking said members to prevent rotation of one member with respect to another.

3. A device of the character stated comprising male and female, elongated members adapted when co-acting to have the longitudinal axes thereof disposed substantially at right angles to one another, said members being shaped and proportioned to provide a disk-like formation in said co-acting relation, and means for interlocking said members to prevent rotation of one member with respect to another.

4. A device of the character stated comprising male and female, elongated members adapted when co-acting to have the axes thereof disposed substantially at right angles to one another, said members being provided with stitch receiving notched slots 80 formed upon arcs of circles adjacent the respective outer ends thereof.

5. A device of the character stated comprising male and female, elongated members adapted when co-acting to have the longitudinal axes thereof disposed substantially at right angles to one another and means for interlocking said members to prevent rotation of one member with respect to another.

105

6. A device of the character stated comprising male and female, elongated members adapted when co-acting to have the longitudinal axes thereof disposed substantially at right angles to one another of which 110 one member is provided with a projection and of which the other member is apertured to accommodate said projection whereby the members may be interlocked to prevent rotation thereof relative to one 115 another.

7. A device of the character stated comprising male and female, elongated members adapted when co-acting to have the longitudinal axes thereof disposed substantially at right angles to one another, the respective members being conversely curved laterally considered so that the combined conversely curved parts form a circular effect in the said co-acting relation of 125 members.

8. A device of the character stated comprising male and female, elongated members adapted when co-acting to have the longitudinal axes thereof disposed substan- 130

tially at right angles to one another, the inversely curved parts permit free egress to
respective members being inversely curved said stitch receiving portions and the com- 10
longitudinally considered and conversely bined conversely curved parts form a circu-
curved laterally considered, there being lar effect.
5 stitch receiving portions provided adjacent In testimony whereof, I have hereunto
said conversely curved parts whereby in affixed my signature.
said co-acting relation of members, said ELIZABETH HONGLER.
